(57) **CLAIM**

The ornamental design for a histotechnology device, as shown and described.

DESCRIPTION

FIG. 1 is a top, front, and left-side perspective view of apparatus and equipment for doctors, hospitals and laboratories according to a first embodiment of the present invention;

FIG. 2 is a top, rear, and right-side perspective view of the apparatus and equipment shown in FIG. 1;

FIG. 3 is a front elevational view of the apparatus and equipment shown in FIG. 1;

FIG. 4 is a rear elevational view of the apparatus and equipment shown in FIG. 1;

FIG. 5 is a right-side elevational view of the apparatus and equipment shown in FIG. 1;

FIG. 6 is a left-side elevational view of the apparatus and equipment shown in FIG. 1;

FIG. 7 is a top plan view of the apparatus and equipment shown in FIG. 1; and,

FIG. 8 is a bottom plan view of the apparatus and equipment shown in FIG. 1.

(Continued)

In the drawings, the equal-length broken lines depict portions of the histotechnology device that form no part of the claimed design.
